UNITED STATES PATENT OFFICE.

SEABORN W. JONES AND ALONZO W. POSTLETHWAITE, OF SAN ANTONIO, TEXAS.

AUTOMATIC CAKE-RACK.

1,171,442.

Specification of Letters Patent.

Patented Feb. 15, 1916.

Application filed September 4, 1914. Serial No. 860,218.

To all whom it may concern:

Be it known that we, SEABORN W. JONES and ALONZO W. POSTLETHWAITE, citizens of the United States, residing at San Antonio, 5 in the county of Bexar, State of Texas, have invented a new and useful Automatic Cake-Rack, of which the following is a specification.

The device forming the subject matter of 10 this application is a display rack adapted to be employed in connection with receptacles of that general type in which crackers, cakes and like merchandise are displayed.

The invention aims to provide a novel 15 means whereby, through the instrumentality of a swinging shelf, the receptacles may be tilted, thereby to effect an opening of the lids thereof, through the medium of flexible elements which are operatively connected 20 with the lids and with the frame upon which the shelf is mounted to swing.

One object of the invention is to provide a novel form of locking mechanism coacting 25 with the shelf to hold the shelf in a rearwardly swung position, thereby to incline the receptacles and to hold the lids thereof open.

It is within the scope of the invention to 30 improve generally and to enhance the utility of devices of that type to which the present invention appertains.

With the above and other objects in view 35 which will appear as the description proceeds, the invention resides in the combination and arrangement of parts and in the details of construction hereinafter described and claimed, it being understood that changes in the precise embodiment of the invention herein disclosed can be made 40 within the scope of what is claimed without departing from the spirit of the invention.

In the accompanying drawing:—Figure 1 is a front elevation showing the structure as the same will appear when the lids on the 45 receptacles are closed; Fig. 2 is a vertical cross section of the structure shown in Fig. 1, the parts in Fig. 2 being disclosed as they will appear when the lids on the receptacles are closed; Fig. 3 is a cross section similar 50 to Fig. 2, but showing the parts as they will appear when the lids are opened, the re-

ceptacles in Figs. 2 and 3 being indicated by dotted line showings.

In carrying out the present invention there is provided a supporting structure or 55 frame which may be of any desired form. In the present instance, the frame is shown as embodying corner posts 1. At the front of the frame, the corner posts 1 are united by a bottom bar 2 and at the rear of the 60 frame, the posts 1 are united by a bottom bar 3. Near the bottom of the frame and at the ends thereof, the posts are united by lower end bars 4. At the front of the frame, the posts 1 are united by a top bar 65 5. At the rear of the frame and at the top thereof, the posts 1 are connected by a rear bar 6. Near to the top of the frame and at the ends of the frame, the posts 1 are united by end bars 7. Extended between 70 the end bars 7 is a longitudinal bar 8. The posts are connected by intermediate end bars 9.

The invention includes a swinging shelf 75 embodying a platform 10, a rear wall 11, a front wall 12 and end walls 14, the latter projecting to an appreciable degree above the upper edges of the other walls. Pivot elements 15 pass through the end walls 14 and enter the intermediate end bars 9. The 80 shelf above described is of symmetrical construction, considered transversely and is adapted to move gravitationally into the position shown in Fig. 2, under which circumstances, the platform 10 will be disposed 85 horizontally.

Mounted upon the platform 10 and retained by the walls 11 and 12 are receptacles 16, each receptacle 16 being equipped with a hinged lid 17.

Eyes 18 are inserted into the forward face 90 of the longitudinal bar 8 and assembled with the eyes 18 are flexible elements 19 which may be light chains or the like. The flexible elements 19 carry hooks 20 which are 95 adapted to be engaged to the forward, free edges of the lids 17 of the receptacles 16.

A brace 21 is located between certain of the receptacles 16, the rear end of the brace 21 being secured as indicated at 22 to the 100 platform 10. At its forward end, the brace 21 is provided with a downwardly prolonged

extension 23 to which is secured a handle 24. This portion 23 of the brace 21 forms a keeper, in which is fashioned a shoulder 25. Below the shoulder 25, the keeper is 5 curved to form a cam 26, the rear edge of which is secured as shown at 27 to the platform portion 10 of the swinging shelf.

The invention includes a latch 28 of any 10 desired form, the same being pivotally connected as shown at 29 with some accessible portion of the frame, as, for instance, the bottom bar 2. The latch 28 is constrained by a spring 30 to bear against the cam portion 26 of the keeper.

15 In practical operation, the parts normally appear as shown in Fig. 2. The platform 10 stands horizontally, the lids 17 on the receptacles 16 are closed, the flexible elements 19 hang slack, and the nose of the 20 latch 28 is constrained by the spring 30 to bear against the lower portion of the cam 26.

Through the medium of the handle 24, the forward edge of the platform 10 may be 25 swung downwardly and rearwardly. Under such circumstances, the cam 26 will ride downwardly along the nose of the latch 28, the latter ultimately hooking over the shoulder 25, the parts then appearing as 30 shown in Fig. 3. By the operation above described, the upper ends of the receptacle 16 will be tilted downwardly and forwardly, thus tightening up the flexible elements 19 and drawing the lids 17 of the receptacles to open positions.

35 When it is desired to restore the parts to the positions shown in Fig. 2, the nose of the latch 28 is disengaged from the shoulder 25 whereupon, under the action of gravity, the swinging shelf and the receptacles 40 thereon will move in the position shown in Fig. 2.

It is to be observed that the spring pressed latch 28, bearing against the keeper,

acts as a cushion when the platform and the receptacle are swung from the position 45 of Fig. 3 to the position of Fig. 2.

Having thus described the invention, what is claimed is:—

In a device of the class described, a frame; a shelf; a receptacle removably mounted on 50 the shelf and having a hinged lid; end walls upstanding from the shelf; pivot elements carried by the frame and engaging the end walls; a flexible member the rear end of which is fixedly connected to the frame, the 55 forward end of which is detachably engaged with the lid adjacent the forward edge of the lid; a spring pressed latch on the frame and a latch-engaging keeper located on the shelf, both of which are independent of the 60 receptacle, the latch and the keeper coöperating to hold the receptacle and the shelf in a forwardly and downwardly tilted position, the latch bearing against the keeper to act as a cushion when the shelf swings forwardly into a horizontal position; and means 65 for preventing the receptacle from sliding off the shelf when the shelf is tilted; the pivot elements engaging the end walls in approximate horizontal alinement with but 70 slightly above the center of gravity of the receptacle when the latter is full, thereby to effect an approximate balancing of the shelf and the receptacle, to prevent undue strains 75 on the flexible member when the receptacle and the shelf are tilted forwardly, and to prevent an inversion of the shelf and the receptacle.

In testimony that we claim the foregoing as our own, we have hereto affixed our signatures in the presence of two witnesses.

SEABORN W. JONES.

ALONZO W. POSTLETHWAITE.
